(57) **CLAIM**

The ornamental design for a mini heat press, as shown and described.

DESCRIPTION

FIG. 1 is a front, bottom perspective view of a mini heat press design showing our new design.

FIG. 2 is a front view of a mini heat press.

FIG. 3 is a rear view of a mini heat press.

FIG. 4 is a left side view of a mini heat press.

FIG. 5 is a right side view of a mini heat press.

FIG. 6 is a top view of a mini heat press.

FIG. 7 is a bottom view of a mini heat press; and,

FIG. 8 is a rear, top perspective view of a mini heat press. The broken lines in the drawings depict portions of the mini heat press that form no part of the claimed design.
